UNITED STATES PATENT OFFICE

CHARLES H. CHALMERS, OF MINNEAPOLIS, MINNESOTA

DESIGN FOR AN OIL BURNER

Application filed February 1, 1932. Serial No. 42,698. Term of patent 14 years.

To all whom it may concern:

Be it known that I, CHARLES H. CHALMERS, a citizen of the United States, residing at Minneapolis, in the county of Hennepin and State of Minnesota, have invented a new, original, and ornamental Design for Oil Burners, of which the following is a specification, reference being had to the accompanying drawing, forming a part thereof, wherein—

Fig. 1 is a plan view of an oil burner showing my new design;

Fig. 2 is a view in side elevation of the same looking towards the right side of the casing, as viewed in Fig. 1; and

Fig. 3 is a rear view of the same.

I claim:

The ornamental design for an oil burner substantially as shown.

CHARLES H. CHALMERS.
